UNITED STATES PATENT OFFICE.

LÝBERAT HUWÝLER, OF GOLDAU, SWITZERLAND.

RAILWAY-CAR.

1,346,891.

Specification of Letters Patent.

Patented July 20, 1920.

Application filed November 7, 1918. Serial No. 261,546.

To all whom it may concern:

Be it known that I, LÝBERAT HUWÝLER, engineer, a citizen of the Swiss Confederation, residing at Goldau, Canton Schwyz, 5 Switzerland, have invented new and useful Improvements in Railway-Cars, of which the following is a specification.

The present invention relates to a new and improved railway baggage or general goods 10 car destined for the transport of goods, cattle and horses. The object of the invention is to provide means which allow the loading and unloading of the car at any place on the line. I attain this object by providing a 15 skid (movable gang-way or ramp) beneath the floor of the car in line with the side doors in such a manner that it can be withdrawn from either side of the car to rest with one end on the earth and with the 20 other on the floor to form an easy gang-way for horses, cattle and so on.

A further object of my invention is to provide means to bring automatically the one end of the skid flush with the floor and 25 to secure the skid automatically in its position beneath the car floor when out of use and in the position in which it is used.

I provide by these automatic guiding and securing means that the skid may be brought 30 and secured in its proper position even by unskilled persons and in the dark, making the device thereby especially useful for military transports when cars have to be loaded or unloaded on the open line by soldiers, etc.

35 It is obvious that by providing each car of the train with a skid all the cars may be loaded and unloaded at the same time and at any place at the station or out of it and much shunting is done away with. By reducing the shunting not only time is saved 40 to a very considerable degree but the general expenses of the railway companies are reduced.

Other objects of my invention relate to 45 the provision of minor parts coöoperating with the elements above noted and details of construction all of which will be more clearly set forth in the following specification.

50 With the above objects in view the invention resides in the parts and combinations of parts hereinafter described and particularly set forth in the claims appended hereto.

In order that my invention may be clearly

understood, I have shown the same in the 55 drawings by way of an example.

Figure 1 shows a goods-car in a side elevation,

Fig. 2 is a section on line A—B of Fig. 1,

Fig. 3 shows parts of the skid and of the 60 guideways therefor connected to the frame of the car on a larger scale,

Fig. 4 shows a part of the guide-ways in side elevation,

Fig. 5 illustrates the locking mechanism 65 for the skid in a top view,

Fig. 6 is a view on the skid from the top, the floor of the car being removed.

In the drawings 1 denotes the floor of a goods car which is provided with two sliding side doors 2, 3. On the lower side of the floor 1 in line with the side doors 2, 3 there are two horizontal guide-ways 4, 5 arranged parallel each other transverse to the car and firmly fixed to the beams 12 of the car frame. 70

Each guide-way is provided at each end with a guide piece 6. On the guide-ways 4, 5 and in horizontal grooves of the piece 6, in line with the said guide-ways 4, 5 run rollers 7 arranged at the corners of a movable skid 8. The skid 8 comprises an iron frame covered by wooden boards, it is strongly built and its length corresponds to the breadth of the car. To secure the skid in 80

its position below the floor 1 I arrange two hooks 9, 10 of equal length both hooks being fixed to a common shaft 11 which is journaled in the beams 12 of the car-frame. On each side of the car the shaft 11 is provided with a handle 15 by means of which the 85 hooks 9, 10 may be brought out of engagement with recesses 13 of the skid 8. To limit the movement of the shaft 11 I arrange two abutments 14 on the beam 12 between which an arm 16 of the shaft 11 plays. The hooks 9, 10 are held and brought in engagement 90 with the skid 8 by gravity. The skid 8 is provided with a ledge 17 on which the hooks 9, 10 slide when the skid 8 is moved on its guide-ways 4, 5. From the ledge 17 the hooks 9, 10 drop in the corresponding cavity 13 95 as soon as the skid assumes its proper position. In each guide piece 6 there is a horizontal groove in line with the guide-ways 4, 5 and a branched-off guide groove 18 leading 100 upwardly and ending in a short horizontal groove 19. To bring the skid 8 in the position for use it is withdrawn from the side

75

of the car from beneath the floor 1. The rollers 7 near the front end, viz., near the end of the person drawing the skid leave the pieces 6 but the rollers 7 on the hind end of the skid pass from the horizontal grooves into the branched-off guide-grooves 18, 19 of the guide pieces 6. The arrangement of the grooves 18, 19 is such that the hind end of the skid 8 is flush with the floor 1 as soon as the rollers 7 enter the grooves 19 to insure a convenient instep of the car (as shown in Fig. 2 in dotted lines.) To make the rollers 7 on the hind end of the skid 8 to pass from the horizontal grooves of the pieces 6 into the grooves 18 I arrange on each piece 6 a switch 20. The switch 20 comprises a double-armed lever which is journaled on a pivot 22. One arm 23, forming a tongue projects into the horizontal groove and forms a part of the guide groove for the rollers 7. The other arm 21 of the lever is provided with a slot 24 into which the end 26 of a second double-armed lever 27 projects and controls the operation of the switch. The lever 27 is rotatably mounted in the guide piece 6 and projects with a curved arm 28 in the path of the skid 8. If the skid 8 rests beneath the floor 1 the arm 28 abuts against the lower side of the skid 8 and the switch 20 assumes the position as shown in Fig. 4. The tongue 23 takes the position shown in which it guides the hind roller 7 into the branched-off groove 18. The skid 8 resting on arm 28 secures the tongue 23 in this position. If the skid 8 is withdrawn into its position for use shown in Fig. 2 by dotted lines, the rollers 7 at the fore part of the skid leave the pieces 6 the rollers 7 at the hind end pass into the grooves 18 and ascend until they bear against abutments 30 resting on springs in the front part 32 of the guide-pieces 6. As soon as the skid 8 leaves the arm 28 the tongue 23 swings upward the weight of the parts 21, 26 exceeding that of the parts 23, 28. To lock the skid 8 in the loading position I provide locking-pins 34 which pass automatically behind the rollers 7 as soon as the latter reach the abutments 30. The pins 34 are made in one with the bar 35 which is movably arranged in suitable bearings fixed to the floor 1. Each bar 35 is provided with a pin 36 and on each pin there is a coiled spring 37 adapted to press the bar 35 and therewith the pins 34 into the groove 19. The bars 35 are linked to the ends of a double-armed lever 33 rotatably mounted on the floor 1 of the car. The locking pins 34 may be simultaneously brought in or out of engagement with the rollers 7. Against each pin 34 rests the free end of a springy slanting bar 39 hinged to piece 6 projecting into the way of the roller 7 in such a manner that the ascending rollers 7 press on the bars 39 and cause said bars to push the pins 34 out of the way of the rollers 7.

As soon as the rollers 7 leave the bar 39 the springs 37 push the pins 34 into the groove 18 and behind the rollers which are now secured against accidental displacement when the skid is used for loading or unloading the car. To secure the bars 35 in their position I provide a lever 41 rotatably mounted on a pin of a bearing fixed to the floor 1. On the pivot of said lever 41 I mount a finger 42 which projects into the path of the roller 7 in the groove 18 and which when swung out rocks the lever 41. On lever 41 there is an arm 43 which projects between two lugs 44, 45 on the bar 35. If the rollers 7 ascend in the grooves 18 they push the fingers 42 aside and the arms 43 leave the bars 35 free to move. To release the skid 8 the bars 35 are withdrawn against the action of the spring 37 by means of handles 46. The rollers 7 on the hind or upper part of the skid 8 descend the groove 18 and the skid may be pushed below the floor. The rollers 7 may pass the switch 20 at the opposite car side the tongue 23 being in its uppermost position. While the skid 8 is moved into the guides 4, 5 the hooks 9, 10 slide on the ledge 17 until they fall into the grooves 13. The skid 8 is now secured in its proper position the ends of it projecting just far enough from the sides of the car to be used as a second tread.

From the foregoing it is obvious that the skid may be withdrawn from any side of the car, in no position does it lose the connection with the car and in no way does it interfere with the general arrangement and design of the car.

It frequently happens that the train moves somewhat while the loading or unloading takes place. I provide therefore rollers on the small sides of the skid in order that the latter may easily follow the car preventing thereby damage.

Foldable railings may be provided which may be used for unloading cattle or I may arrange rails at the side walls of the car which could be used for railings in case of need.

Various details of construction for instance the means for locking the skid in its positions, etc., may be varied without departing from the spirit of the invention.

Also I have described the preferred form of construction. I wish it understood that various details of construction may be changed without departing from the spirit of the invention.

What I claim and wish to secure by Letters Patent of the United States is:

1. In a railway car, a skid having rollers on opposite sides near each end; skid supporting members under the car, including horizontal guides in which said rollers operate and also including inclined guides for said rollers, and gravity acting switches in

the angles between said horizontal and inclined guides.

2. A railway car comprising in combination a skid, rollers on said skid, two guide-ways fixed transversely beneath the car floor in line with the side doors of the car, a guide piece at each end of each guide-way, each guide piece having a horizontal groove and a branched-off groove for said rollers, switches to lead the rollers into said branched-off groove, means to set the switches and means to secure the skid when in and out of use.

3. A railway car comprising in combination a skid, rollers on said skid, two guide-ways fixed beneath the car floor in line with the side doors of the car, a guide piece at each end of each guide-way, each guide piece having a horizontal groove in line with the corresponding guide-way and an ascending groove branched-off from said horizontal groove, switches to lead the rollers from the horizontal to the ascending groove, each switch comprising a tongue projecting into the path of the rollers, means to set said switch by gravity and by the skid and means to lock the switch when in one position.

4. A railway car comprising in combination a skid, rollers on said skid, two guide-ways fixed beneath the car floor in line with the side doors of the car, a guide piece at each end of each guide-way, each guide piece having a horizontal groove in line with the corresponding guide-way and an ascending groove branched-off from said horizontal groove, switches to lead the rollers from the horizontal to the ascending groove, each switch comprising a tongue projecting into the path of the rollers, means to set said switch by gravity and by the skid and

means to hold the skid firmly in its position substantially as described for the purpose set forth.

5. In a railway car, a skid having rollers on opposite sides near each end; skid supporting members under the car, including horizontal guides in which said rollers operate and also including inclined guides for said rollers, and gravity acting switches in the angles between said horizontal and inclined guides, and controlling means for the switches, said controlling means being held in operative position by the skid when the latter is in normal withdrawn position. 55

6. In a railway car, a skid having rollers on opposite sides near each end; skid supporting members under the car, including horizontal guides in which said rollers operate and also including inclined guides for 60 said rollers, gravity acting switches in the angles between said horizontal and inclined guides, and retaining means to engage behind the rollers when the latter reach the upper ends of the inclined guides and the 65 skid is in extended, operative position.

7. In a railway car, a skid having rollers on opposite sides near each end; skid supporting members under the car, including horizontal guides in which said rollers operate and also including inclined guides for 70 said rollers, gravity acting switches in the angles between said horizontal and inclined guides, retaining means to engage behind the rollers when the latter reach the upper 75 ends of the inclined guides and the skid is in extended, operative position, and operating means for the retaining means and including members arranged in said inclined guides in the paths of the skid rollers. 80

In testimony whereof I affix my signature.
HUVYLER LYBERAT.
